(57) **CLAIM**

The ornamental design for a waste container, as shown and described.

DESCRIPTION

FIG. 1 shows a front view of an embodiment of a first embodiment of a waste container embodying my new design;

FIG. 2 shows a right side view of the waste container as shown in FIG. 1;

FIG. 3 shows a bottom view of the waste container as shown in FIG. 1;

FIG. 4 shows a top view of the waste container as shown in FIG. 1;

FIG. 5 shows a left side view of the waste container as shown in FIG. 1;

FIG. 6 shows a rear view of the waste container as shown in FIG. 1;

FIG. 7 shows an upper perspective view of the waste container as shown in FIG. 1;

FIG. 8 shows a front view of a second embodiment of a waste container embodying my new design;

FIG. 9 shows a right side view of the waste container as shown in FIG. 8;

FIG. 10 shows a bottom view of the waste container as shown in FIG. 8;

FIG. 11 shows a top view of the waste container as shown in FIG. 8;

FIG. 12 shows a left side view of the waste container as shown in FIG. 8;

FIG. 13 shows a rear view of the waste container as shown in FIG. 8; and,

FIG. 14 shows an upper perspective view of the waste container as shown in FIG. 8.
